UNITED STATES PATENT OFFICE.

FREDERICK H. SECORD, OF CHICAGO, ILLINOIS.

LUNCH-COUNTER.

SPECIFICATION forming part of Letters Patent No. 723,043, dated March 17, 1903.

Application filed September 8, 1902. Serial No. 122,535. (No model.)

To all whom it may concern:

Be it known that I, FREDERICK H. SECORD, a citizen of the United States of America, and a resident of Chicago, in the county of Cook 5 and State of Illinois, have invented certain new and useful improvements in Lunch-Counters, of which the following is a specification.

The main object of my invention is to provide an improved construction for lunch-10 counters, being rigid, simple in structure, and inexpensive and having improved facilities for cleaning the upper surface of same and for arranging receptacles for condiments in suitable position to be handy for each individual patron. I accomplish this object by 15 the device shown in the accompanying drawings, in which—

Figure 1 is a transverse section of a lunch-20 counter constructed according to my invention. Fig. 2 is a perspective view of the same, partly broken away.

The structure shown consists of a flat top 1, horizontally disposed and supported by a plurality of posts 2. The posts 2 are located 25 a considerable distance forward of the rear edge 3 of the counter-top, and the space between the posts is ceiled by the vertical panels 4. The top 1 is rigidly secured to the posts 2 by means of the angle-pieces 5 and 6. 30 Similar angle-pieces 7 secure the posts to the floor. A brace 8 connects the forward ends of the angle-pieces 6 and 7 and is sprung inwardly and secured to the post 2 at 9, thus forming a rigid supporting-frame for the top 35 1 of the counter.

The top 1 of the counter is subdivided into spaces each of sufficient length for a single patron by means of a plurality of brackets 40 10. Each of the brackets 10 consists of a rectangular back 11, disposed vertically and extending along the rear edge 3 of the top 1 and having rigidly secured at each end a triangular arm 12. The forward ends of the arms 12 are pivotally secured, by means of the 45 bolts 13, to the plates 14, which are rigidly secured to the table 1. Rubber buffers 15 are provided to prevent the brackets 10 from marring the surface of the top 1. Boxes 16 for knives, forks, and spoons are secured to 50 the rear side of the panels 4 at suitable intervals along the counter. The panel 4 is also provided with a shelf 17, which extends

along the entire length of the counter and serves as a rack for tumblers, &c.

The operation of the device shown is as 55 follows: The spaces 18 between the arms 12 of adjacent brackets 10 serve as racks for supporting bills of fare and other announcements. The brackets 10 form suitable racks along which receptacles for condiments may 60 be placed in suitable position to be conveniently accessible to the patron. When the top of the table is to be cleaned, the bracket 10 may be turned on its pivot 13, so that all parts of the top 1 are easily accessible from 65 the rear side of the counter.

It will be seen that the space occupied by each individual patron is entirely independent of any of the other spaces along the counter and that each of said spaces may be readily cleaned while the adjacent spaces are in use.

It will be seen that numerous details of the device shown may be altered without departing from the spirit of my invention. I therefore do not confine myself to such details except as hereinafter limited in the claims.

What I claim as my invention, and desire to secure by Letters Patent, is—

1. In a lunch-counter, the combination of a 80 counter having a flat top; a back 11 having rigidly secured thereto the side arms 12, and suitable means for pivotally securing the free ends of said arms to the top of said counter, substantially as and for the purpose specified. 85

2. In a lunch-counter, the combination of a counter having a flat top; a bracket comprising a substantially rectangular back having rigidly secured thereto at each end of same a side arm, said arms being substantially triangular in shape; and suitable means for pivoting the free ends of said arms to the top of said counter, substantially as and for the purpose specified. 90

3. In a lunch-counter, the combination of a 95 counter having a flat top; a plurality of back pieces, each having rigidly secured thereto and extending forward from each end thereof a side arm, said side arms being pivoted to said top in suitable manner to divide said top into a plurality of spaces, separated by double partitions, substantially as and for the purpose specified. 100

4. In a lunch-counter, the combination of a

top 1; a supporting-wall 4; a plurality of braces 8, connecting said top with said wall and sprung inwardly near the middle of the height of said wall; and a plurality of brackets 10 pivotally secured to said top, substantially as and for the purpose specified.

5. A lunch-counter, comprising a vertical supporting-wall; a horizontally-disposed table-top secured upon said wall and extending beyond the front and rear face of the wall so as to form a short overhanging ledge at the rear face and a long overhanging ledge at the front face of said wall; a plurality of bracing-strips 8 secured under the front ledge, 15 sprung inwardly and secured to the front face of the wall near the middle of its height and extending forward at the base; and a shelf secured to and extending along the rear of said wall and protected by said rear ledge, 20 substantially as described.

6. A lunch-counter provided with a plurality of brackets arranged upon the top of the counter side by side along the rear part thereof, each of said brackets forming an 25 closure open toward the front, suitable to retain bottles, &c., to prevent same from being pushed off from the rear of the counter, and each pivoted at its forward part to the top of the counter, substantially as and for the purpose specified.

7. A lunch-counter provided with a plurality of brackets secured upon the top of the counter side by side along the rear part thereof, each consisting of a back piece extending 30 along the rear edge of the counter and hav-

ing a side arm extending forward from each end of the back piece, said brackets being suitably secured to permit accumulations on said counter to be wiped or brushed flush with the top of the counter and over its rear 40 edge, substantially as described.

8. A lunch-counter provided with a plurality of brackets pivotally secured upon the top of the counter side by side along the rear part thereof, each consisting of a back piece 45 extending along the rear edge of the counter and having an arm extending forward from said back piece, substantially as and for the purpose specified.

9. A lunch-counter provided with a plurality of brackets secured upon the top of the counter side by side along the rear part thereof, each consisting of a back piece extending along the rear edge of the counter, and having an arm extending forward from said back 50 piece, said brackets being suitably secured to prevent same from being pushed over the rear edge of the counter and arranged to have said back pieces moved free from the top of the counter to permit accumulations on said 55 counter to be wiped or brushed flush with the top thereof and over its rear edge, substantially as described.

Signed at Chicago this 6th day of September, 1902.

FREDERICK H. SECORD.
